ABSTRACT OF THE DISCLOSURE

A device which comprises a holding member on a support for the reception of a guide bearing or dental handpiece sleeve to which a dental tool is to be secured, the bearing or sleeve having a built-in collet chuck rotatable by a driving wheel to secure or release the tool. The holding member has a mating drive wheel which is rotatable and longitudinally displaceable for operating the chuck, means being provided on the support for restraining displacement of said bearing or sleeve so that a tool can be secured or released by appropriate rotation of the mating drive wheel.

BRIEF SUMMARY OF THE INVENTION

The invention relates to a device for the fixing and unfixing of a tool, such as a burr, in a dental handpiece, or in a guide bearing adapted to be inserted in such a handpiece, and wherein the tool is held by means of a built-in collet chuck.

It is known that tools can be interchanged by manual manipulation by operating locking elements arranged on the handpiece. The manual operations required for this are very laborious.

An object of the invention is to provide a device which makes it possible for a dentist when treating a patient no longer to have to remove a tool from a handpiece in a laborious manner to replace it by another more suitable tool.

The device according to the invention is characterized by a holding member which is arranged on a support and to which there can be attached a guide bearing, or a handpiece sleeve released from the remainder of the handpiece so that a driving wheel of the guide bearing or handpiece sleeve can be engaged with a mating driving wheel mounted for longitudinal displacement and rotation in the holding member, the mating driving wheel having a shaft which projects from the free end of the holding member, and the support having an abutment wall for the tool-region end of the handpiece sleeve or guide bearing, and having also latching means for preventing rotation of a handpiece sleeve or guide bearing when mounted in the device.

By means of the device according to the invention for the fixing and unfixing of tools, it is possible for a dental nurse or dentist, before treating a patient, to prepare a relatively small number of guide bearings or handpiece sleeves which are provided with the most commonly used tools and which can then be connected to

2

the remainder of the handpiece, in known manner, by simply fitting-on and securing by means of a screwthread or bayonet joint, during treatment of the patient. In this way the dentist always has available lubricated, sterilized and checked handpiece sleeves or guide bearings ready and available with the tool in question. Generally six to eight handpiece sleeves or guide bearings with different tools in each case will be sufficient.

The holding member may be arranged on the support so as to be upwardly and downwardly pivotable to facilitate insertion and removal of the guide bearing.

In accordance with a further embodiment of the invention, the holding member may be constructed as a mandrel on which or into which the handpiece sleeve or guide bearing is adapted to be applied or inserted as appropriate.

The holding member, constructed as a mandrel, may comprise an axial, forwardly open housing more particularly for the insertion of the guide bearings.

The holding member may also be arranged non-movably on the support and the spacing between the abutment and the withdrawn mating driving wheel may be such that the guide bearing can be inserted from above into the support.

The latching means may conveniently comprise projections provided on the abutment wall and recesses arranged at the tool-region end of the handpiece sleeve or guide bearing. This form of embodiment has the advantage that the recesses arranged at the tool-region end of the handpiece sleeve or guide bearing may serve as salvia deflectors.

For easier operation of the fixing device, the free end of the shaft of the mating driving wheel may be provided with a rotatable knob.

The manipulation of the fixing device may be further facilitated by so arranging the shaft of the mating driving wheel that it can be displaced in the direction towards the abutment in opposition to the action of a spring.

The support may also be provided with a downwardly directed grip to facilitate the secure holding of the fixing device.

45 BRIEF DESCRIPTION OF THE DRAWING

FIG. 1 is a longitudinal sectional view of a device according to the invention showing a guide bearing to be inserted in the device,

FIG. 2 is a longitudinal sectional view of the device according to FIG. 1 with the guide bearing inserted in the fixed position,

FIG. 3 is a plan view of the device according to FIG. 2 from above,

FIG. 4 is a detail view showing the tool-region end of a guide bearing or handpiece sleeve,

FIG. 5 is an internal perspective view showing an abutment of the fixing device according to FIGS. 1 to 3,

FIG. 6 is a longitudinal sectional view of a guide bearing with a tool fixed therein,

FIG. 7 is a longitudinal sectional view of a modified form of embodiment of the invention with inserted guide bearing,

FIG. 8 is a longitudinal sectional view showing a device according to the invention with a handpiece sleeve inserted, in the fixed position, and

FIG. 9 is a plan view of the device according to FIG. 8 from above.

DETAILED DESCRIPTION

In the drawing, 1 designates a support which is provided at one end with a holding member 2. At the opposite end of the support 1 is an abutment 4 which is provided with an indentation 5, as shown in FIG. 5.

A driving wheel 7 is mounted by means of a shaft 6 in the holding member 2 so as to be rotatable and longitudinally displaceable. The shaft 6 is provided at its free end with a rotatable knob 8.

In the form of embodiment shown in FIGS. 1 to 3, the support 1 comprises side walls 1a. Moreover in this form of embodiment and in the form of embodiment shown in FIG. 7, the shaft 6 of the driving wheel 7 is adapted to be displaced in a direction towards abutment 4 in opposition to the action of a coil spring 9 encircling shaft 4. As shown in detail in FIGS. 1 and 5, projections 10 are arranged at both sides of the indentation 5 of the abutment 4.

The devices shown in FIGS. 1 to 3 and 7 are used for the detachable connection of a tool 13 in a long guide bearing 11 as shown in FIG. 6, while the device according to FIGS. 8 and 9 is suitable for installing a tool in handpiece sleeve 12 which is separated from the remainder of the handpiece. The dental tool 13 (a burr in the embodiments illustrated) is mounted by means of a collet chuck 14 either in the guide bearing 11 as shown in FIG. 6 or in the handpiece sleeve 12 as shown in FIG. 8. The clamping jaws of the collet chuck 14 can be forced together or shifted into the opened position by means of a clamping nut 15 adapted to be screwed externally onto the jaws, by appropriate rotational movement. The tool 13 is clamped fast in the forced-together position of the said jaws.

As FIG. 4 shows in detail, the tool-region end of the clamping nut 15 is formed with recesses 16.

In the embodiment according to FIGS. 8 and 9 the support 1 has a downwardly directed grip 21.

The driving wheel of the guide bearing 11 or of the handpiece sleeve 12, is designated by numeral 17 and is mounted for rotation jointly with the collet chuck 14.

The device according to the present invention is operated as follows:

To secure the tool 13 in guide bearing 11, the tool is inserted in the open collect chuck. Then the guide gear-bearing 11 is inserted with its drive-side end into the housing 18 of the holding member 2, the driving wheel 17 engaging with the mating driving wheel 7. Then the holding member 2, hitherto swung upwardly as shown in FIG. 1, is swung down with the guide bearing 11 into the horizontal position shown in FIG. 2. In the embodiment according to FIG. 7, the guide bearing 11 is simply placed in the support 1 from above. By axially pressing the rotatable knob 8, the shaft 6 is then moved, in opposition to the action of the spring 9, in the direction towards the abutment 4 until the tool-region end, i.e. the face of the clamping nut 15 abuts against the abutment 4, the tool 13 having previously entered the indentation 5 during the swinging-down movement in the case of the embodiment of FIG. 1 or during placement of the bearing 11 into the support in the case of FIG. 7. When the rotatable knob 8 is slightly turned by an appropriate extent as may be necessary while the knob is also being pressed, the recesses 16 of the clamping nut 15 come into engagement with projections 10 of the abutment 4. By then turning the rotatable knob 8, the collet chuck is rotated in the clamping nut to force the jaws of the collect chuck 14 together, until the tool 13 is securely clamped in the jaws. Thereafter, the holding member is disengaged from the abutment in the form of embodiment according to FIGS. 1 to 3 by being pivoted upwards, so that the guide bearing 11

with the fully fixed tool 13 can be removed. In the embodiment of FIG. 7, the guide bearing 11 with tool 13 fixed therein is removed by releasing knob 8 which is then retracted by spring 9 to release bearing 11 which may then be manually removed.

5 Manipulation of the embodiment according to FIGS. 8 and 9 can be carried out in a manner similar to that described above with reference to the embodiments of FIGS. 1 and 7. However, in the case of the embodiment of FIG. 8, the holding member 2 need not be of hollow construction and on the contrary, since the hand-piece sleeve 12 itself has an appropriate cavity 19, the member 2 can be constructed as a solid, rotatable mandrel so that the hand-piece sleeve 12 can be fitted onto the holding member 2 until the driving wheel 17 engages with the mating driving wheel 7. Otherwise the method of operation corresponds to that already described in connection with FIGS. 1 to 3 and 7. Namely, after the recesses 16 in nut 15 are engaged by projections 10, the knob 8 is turned to clamp the jaws of the chuck 14 on the tool 13 and thereby lock the latter in the sleeve 12. Then the sleeve 12 with the tool 13 secured therein is removed from the holder 2.

10 The finished guide bearing 11 can be fixed in a hand-piece in a suitable manner by tightening a screw ring or the like in the point of handpiece. The fixing of the handpiece sleeve 12 on the handpiece is effected by locking an appropriate bayonet dog or the like on the handpiece (not shown) in a bayonet slot 20 on sleeve 12.

15 In the aforescribed embodiments, a supply hose for supplying a spray may be provided, and such supply hose can easily be fitted-on in known manner.

20 From the above it is seen that there has been provided, the combination of a support member (guide bearing 11 or sleeve 12) for a dental tool 13, and a device for securing and releasing the tool in the support member, the latter device comprising holding means constituted by support 1 and holder 2 for receiving the support member, and means, in the form of drive wheel 7 and abutment wall 4 (with projections 10 thereon) for acting on collet 25 lease such jaws.

What is claimed:

1. In combination, a support member including a chuck for holding a dental tool, said chuck having jaws chuck 14 to clamp the jaws thereof on the tool or to release for clamping the tool, a clamping nut threadably engaged on the chuck in the region of the jaws for clamping the jaws on the tool, a holder for receiving said support member and including a rotatable drive wheel, said support member including a wheel coupled to the chuck for rotating the same and engageable by the drive wheel to be driven in rotation thereby, and abutment means on said holder for engaging the clamping nut to hold the same against rotation such that by turning the drive wheel and thereby also the chuck, the jaws can be clamped or unclamped on the tool depending on the direction of rotation.

2. The combination as claimed in claim 1 wherein said drive wheel is axially displaceable and in a first position is spaced from the wheel on the support member whereas in a second axially displaced position the drive wheel is engaged with the wheel on the support member, said abutment means including an abutment wall for limiting displacement of the clamping nut and thereby of the support member and driving wheel.

3. The combination as claimed in claim 2 wherein said abutment means includes latching means on said wall for engaging the clamping nut to hold the same fixed in rotation.

4. The combination as claimed in claim 3 wherein said holder comprises a fixable support and a pivotable member on said support, said drive wheel being mounted in said pivotable member, said abutment means being mounted on said fixable support, said pivotable member being pivotable to a raised position for insertion and removal of the support member with tool, and to a lowered position in

which the tool is secured or released from the support member.

5. The combination as claimed in claim 3 wherein said holder comprises a fixable support on which said drive wheel and abutment means are mounted, said fixable support being constituted as a mandrel to enable said support member and tool to be engaged therewith.

6. The combination as claimed in claim 5 wherein said support member is freely insertable or removable from the fixable support.

7. The combination as claimed in claim 5 wherein said support member is in the form of a sleeve which can be fitted on said fixable support.

8. The combination as claimed in claim 3 wherein said holder comprises a fixable support on which said abut-

ment means is mounted, and a member which supports the drive wheel for axial and rotatable movement, said drive wheel including a shaft extending externally of the holder for being manually operated to displace and rotate the drive wheel.

5 9. The combination as claimed in claim 1 wherein said support member has opposite ends, said drive wheel being at one end and the clamping nut at the other.
